(57) **CLAIM**

The ornamental design for a stapling head feature for a surgical stapler, as shown and described.

DESCRIPTION

FIG. 1 is a top perspective view of a stapling head feature for a surgical stapler, showing our new design;

FIG. 2 is a bottom perspective view of the stapling head feature for a surgical stapler of FIG. 1;

FIG. 3 is a front elevational view of the stapling head feature for a surgical stapler of FIG. 1;

FIG. 4 is a rear elevational view of the stapling head feature for a surgical stapler of FIG. 1;

FIG. 5 is a left elevational view of the stapling head feature for a surgical stapler of FIG. 1;

FIG. 6 is a right elevational view of the stapling head feature for a surgical stapler of FIG. 1;

FIG. 7 is a top plan view of the stapling head feature for a surgical stapler of FIG. 1;

FIG. 8 is a bottom plan view of the stapling head feature for a surgical stapler of FIG. 1;

FIG. 9 is a cross-sectional view of the stapling head feature for a surgical stapler of FIG. 1, taken along line 9-9 of FIG. 7; and,

FIG. 10 is a cross-sectional view of the stapling head feature for a surgical stapler of FIG. 1, taken along line 10-10 of FIG. 7.

The evenly-spaced broken lines in the drawings are included for purpose of illustrating portions of the staple head feature for a surgical stapler that form no part of the claimed design. The dot-dash-dot broken lines in the drawings are included for the purpose of defining the boundary of the claim, it being understood that the dot-dash-dot broken lines themselves form no part of the claimed design. The defined boundary represents a repeatable unit of the claimed design.
